CLAIM

The ornamental design for a hydrotherapy massage unit for bath tubs or the like, substantially as shown.

DESCRIPTION

FIG. 1 is a perspective view of a hydrotherapy massage unit for bath tubs or the like showing our design including a central box, a stationary device, and a movable device;

FIG. 2 is a front elevational view of the control box as shown in FIG. 1;

FIG. 3 is a rear elevational view of the control box as shown in FIG. 1;

FIG. 4 is an end elevational view of the control box as shown in FIG. 1;

FIG. 5 is an end elevational view of the control box as shown in FIG. 1 opposite the end shown in FIG. 4;

FIG. 6 is a top plan view of the control box as shown in FIG. 1;

FIG. 7 is an elevational view of the movable device as shown in FIG. 1;

FIG. 8 is a top plan view of the movable device as shown in FIG. 1;

FIG. 9 is a top plan view of the stationary device as shown in FIG. 1;

FIG. 10 is an elevational view of the stationary device as shown in FIG. 1;

FIG. 11 is an end elevational view of the stationary device as shown in FIG. 1;

FIG. 12 is an end elevational view of the stationary device as shown in FIG. 1 opposite the end shown in FIG. 11.
